UNITED STATES PATENT OFFICE

JOSEPH JONES MUNSON, OF HOUma, LOUISIANA

CENTRIFUGAL MACHINE

Application filed September 25, 1928. Serial No. 308,265.

This invention relates more especially to continuously operating centrifugal separating machines of the type shown, described and claimed in my copending application, Serial No. 118,131, which was filed in the United States Patent Office under date of June 23, 1926.

The main object of my invention is to provide an improved construction, combination and arrangement of parts in a machine of this character whereby a more effective separation of ingredients may be secured, and whereby the machine may be more economically operated and whereby the machine may be better adapted to withstand the wear and tear of continuous active service.

Another object of my invention is to provide a centrifugal machine of improved construction whereby a better distribution of stresses and strains may be secured and an improved balance maintained in the operations of the several parts.

My invention contemplates a centrifugal separating machine in which a plurality of cylindrical baskets are symmetrically arranged with respect to a common axis about which they revolve, while at the same time rotating planetarily on their own axes. In machines of this nature, the cylindrical baskets which receive the materials to be separated, may be caused to rotate by means of an eccentric loading of a series of peripheral compartments with which said baskets are provided, the velocity of these planetary movements depending upon the rapidity with which the materials are supplied thereto.

Other and further objects of invention will appear in the specification, the particular features relating thereto being recited in the claims in connection with the accompanying drawings which exemplify my invention in a preferred embodiment.

In the drawings—

Figure 1 is a top plan view of a preferred

embodiment of my improved centrifugal separating machine.

Figure 2 is an enlarged section on the line 2—2 of Figure 1, parts being broken away and parts shown in elevation.

Figure 3 is an enlarged fragmentary section on the line 3—3 of Figure 1, parts being broken away and parts shown in elevation.

Figure 4 is an enlarged transverse section of one of the baskets; and

Figure 5 is a section on the line 5—5 of Figure 2, parts being shown in section.

Referring more particularly to the drawings, an outer fixed housing of the machine comprises an imperforate cylindrical wall 1 surmounted by a peripheral top flange 2. A hopper 3 depends from the lower edge of the cylindrical wall 1, a conical plate or wall 4 which is presented upwardly and inwardly from around the lower edge of the cylindrical wall 1 being arranged to form an annular trough which discharges outwardly through outlet pipes 5.

Centrally arranged with respect to and depending within the stationary housing is a rotary shaft 6 which constitutes a preferred means for rotating a movable housing to be presently described. The rotary shaft 6 is provided near its lower end with a conical surface 7 below which extends a threaded reduced end 8. Mounted upon the conical portion 7 of the shaft 6 is the hub 9 of a spider frame comprising radial arms 10. A nut 11 which is threaded to the reduced end 8 of the shaft 6 secures the spider frame to said shaft, a check-nut 12 being provided to retain the nut 11 in position. Each of the radial arms 10 of the spider frame is provided with a plate or flange 14, and an arcuate lug 15 which interlocks with a corresponding recess formed around the inner edge of an annular plate 16 which is secured in position by means of bolts 17. Annular plate 16 constitutes the base of a rotary housing which includes a cylindrical wall 18 and an upper annular

plate 19. The annular plates 16 and 19 are presented inwardly from the upper and lower edges of the cylindrical wall 18 and in effect form an annular chamber which revolves around the axis of shaft 6. Within this annular chamber is collected the separated liquids which may be discharged outwardly through suitable openings 18^a formed along the lower edge of cylindrical wall 18. The liquids which are thus thrown off by centrifugal force, drain into the annular trough formed between the cylindrical wall 1 and the conical plate 4 and flow from thence through the outlets 5.

15 A distributor bowl 20 which is rotatable with and relatively to the shaft 6, is provided with a hub portion 21 which is freely journalled upon the shaft 6 and axially supported by means of a collar 22 secured to said shaft. Said distributor bowl is provided with a central opening 23 through which the shaft 6 depends and into which depends the outlet end 24 of a supply pipe 25. The distributor bowl is provided around its upper peripheral 25 edge with an annular chamber 26 into which water may be discharged from a pipe 27.

Symmetrically arranged with respect to the rotary shaft 6, as shown in Figure 1, are a plurality of planetary baskets, said planetary baskets being movably supported in a peculiar way. As shown in Figures 2, 3, and 4, each of said planetary baskets comprises an outer cylindrical wall or plate 28 provided with perforations, an inner screen 29 of fine mesh, and with upper and lower annular cap-plates 30 and 31 which are provided with upwardly and downwardly presented flanges or treads 32 which roll upon and are supported by the annular plates or track-bars 16 and 19. Depending from the distributor bowl 20 within each of the planetary baskets, is a spout 33 provided with an inwardly-presented orifice 34 which is thus arranged to discharge into successive compartments 35 which are formed within the cylindrical wall 28 by means of rearwardly deflected partitions 36. As shown best in Figure 3 of the drawings, each of the spouts 33 is provided with a laterally-presented flange or plate 37 by means of which it is rigidly connected to a side wall of a chute or baffle 38 which as shown in Figure 4 is provided with a trough-like cross-section and which in side elevation as shown in Figure 2, is approximately triangular. Each of the opposite lateral walls of baffle 38 is provided with a base flange 39. As indicated in Figures 2 and 4, all of the base flanges 39 are rigidly connected to and serve to support a bottom bearing plate 40 which is provided at its center with a bushing 41 which rotatably bears on the shaft 6. It will be understood from this description that the distributor bowl 20, depending spouts 33, baffles 38, and bottom bearing plate 40 together con-

stitute a rotary inner frame which is journalled upon the shaft 6 and rotatably supported by the collar 22. Suitable means for retaining the planetary baskets in proper cooperative relation to the several spouts 33 70 may be provided as follows. Referring to Figures 1, 3, and 5, it will be seen that each of the depending spouts 33 is provided with a laterally-presented lug 41^a in which is mounted a stud 42. Projecting laterally 75 from a lateral wall of each baffle 38 and arranged oppositely with respect to the lug 41^a, is another lug 43 which carries a stud 44. Journalled upon the studs 42 and 44 are rollers 45 which bear against the inner wall 80 of circular flange or tread 32, said rollers cooperating with the circular track 19 in rotatably supporting each of the planetary baskets against undue displacement under the action of centrifugal force while at the same time operating to revolve the central supporting frame around the shaft 6 whenever an eccentric loading of the planetary baskets causes them to travel around the track-bar 19.

It will be understood that when the machine is at rest, the planetary baskets are permitted to sag toward the rotary shaft 6 by reason of the downwardly sloping top surfaces of the upper cap rings 30, the lower treads 32 being in bearing engagement with the bottom bearing plate 40 until the speed of the machine becomes sufficient to displace the planetary baskets outwardly under the action of centrifugal force.

When the machine is in use, the material to be treated is permitted to flow into distributor bowl 20 from pipe 25 during the rapid whirling of the planetary baskets about the axis of shaft 6. If, for example, massecuite 105 is thus discharged into distributor bowl 20, it is thrown outwardly against the inner wall of said bowl, forming itself into an annular mass. Under high velocity this mass builds up with a substantially vertical inner wall 110 which as it reaches the discharge openings 34 of the spouts 33, begins to spill out into the peripheral chambers 35 of the planetary baskets. During the progress of this operation the planetary baskets are caused to rotate on their own axes under an eccentric loading of the chambers 35 as fully explained in my above identified copending application, Serial No. 118,131. After all of the planetary baskets have become fully loaded, the eccentric loading thereof will remain due to the fact that the molasses content of the massecuite in chambers 35 which are moving outwardly from the axis of shaft 6 is of greater weight than that of the massecuite contained 115 within the chambers 35 which are moving inwardly on the opposite side of the rotary axis of each of said baskets owing to the separation of the molasses therefrom. The effect 120 of this condition is to maintain the drying 130

baskets in slow rotation at a speed which varies with the rate at which massecuite is introduced thereto. When and if desired, water may be supplied to the massecuite in chambers 35 by means of perforated pipes (not shown) connected up with the annular water chamber 26 and discharging into said chambers.

I claim:—

10 1. In a centrifugal machine, the combination of a rotary housing, a cylindrical screen arranged between the axis of said rotary housing and the peripheral wall thereof, said cylindrical screen being freely rotatable about its own axis and progressively movable along the peripheral wall of said rotary housing.

20 2. In a centrifugal machine, the combination with a rotary cylindrical housing, of a rotary cylindrical separator basket rotatable about an axis revolvable around the axis of and relatively to said rotary cylindrical housing, said separator basket having rolling contact with said rotary cylindrical housing whereby said separator basket is adapted by its own rotation to propel itself relatively to said rotary cylindrical housing and around the axis thereof.

30 3. In a centrifugal machine, the combination of a rotary housing, and a separator basket rotatable on an axis which revolves around the axis of said rotary housing, said separator basket being in progressive rolling contact with said rotary housing over a path which is concentric to the rotary axis of said housing.

40 4. In a centrifugal machine, the combination of a rotary cylindrical housing provided with a track extending around and concentric with the rotary axis of said housing, and a plurality of rotary cylindrical separator baskets freely rotatable on axes revolvable about the rotary axis of said cylindrical housing and having rolling contact with said track for propelling them progressively around the cylindrical wall of said rotary housing.

50 5. In a centrifugal machine, the combination with a rotary housing provided with an inwardly-presented track-rail, of a planetary basket revolvable about the axis of said rotary housing and having a portion thereof in rolling engagement with said inwardly-presented track-rail, a distributor bowl rotatable about the axis of and relatively to the rotary housing, and spouts depending within said planetary baskets respectively, said distributor bowl being provided with anti-friction rollers movably engaging said rolling portions of each of the planetary baskets.

60 6. In a centrifugal machine, the combination with a rotary housing provided with an inwardly-presented track-rail of a plurality of planetary baskets revolvable about the axis of said rotary housing said baskets being provided with treads in rolling engagement with

said inwardly-presented track-rail, a distributor bowl concentric with and rotatable relatively to said rotary housing, said distributor bowl being provided with spouts depending within said planetary baskets respectively, and a rotary disk connected to said spouts and movable relatively to said rotary housing around the axis of the latter.

7. In a centrifugal machine, the combination with a rotary housing provided with axially-spaced inwardly-presented track-rails, a plurality of planetary baskets revolvable about the axis of said rotary housing, said baskets being provided with axially-spaced treads in rolling engagement with said inwardly-presented track-rails, and a distributor bowl concentric with said axis of the rotary housing and discharging into said planetary baskets respectively, and means for holding the rotary axes of said planetary baskets in fixed relation to the rotary axis of said distributor bowl, said distributor bowl and planetary baskets being movable together as a unit relatively to said rotary housing.

8. In a centrifugal machine, the combination with a housing rotatable on an axis, said housing being provided with axially-spaced inwardly-presented track-rails, a plurality of planetary baskets revolvable about the axis of said rotary housing, said baskets being provided with axially-spaced treads in rolling engagement with said inwardly-presented track-rails, a distributor bowl rotatable upon said axis and relatively to the rotary housing, said distributor bowl being provided with spouts depending within said planetary baskets respectively.

9. In a centrifugal machine, the combination with a rotary shaft, of a rotary housing rotated by said shaft, a plurality of planetary baskets rotatable about axes which travel around the axis of said shaft, said baskets rotatably engaging said rotary housing and having progressive movement along the peripheral wall and around the axis of said rotary housing, and a supporting frame rotatable on and relatively to said shaft, said supporting frame movably engaging said planetary baskets.

10. In a centrifugal machine, the combination with a rotary shaft, of a rotary housing carried by said shaft, a plurality of planetary baskets rotatable about axes which travel around the axis of said shaft, said baskets being in rolling engagement with said rotary housing and movable progressively along the peripheral wall of said rotary housing, a unitary supporting frame for said baskets rotatable on and relatively to said shaft, and means carried by said unitary supporting frame for rotatably engaging said planetary baskets.

11. In a centrifugal machine, the combination of a pair of axially-spaced track-bars rotatable on a common axis, a plurality of

- planetary baskets in rolling contact with said axially-spaced track-bars, said planetary baskets being rotatable about axes symmetrical disposed with respect to said common axis, means rotatable relatively to said common axis for rotatably supporting said planetary baskets in rolling engagement with said axially-spaced track-bars.
12. In a centrifugal machine, the combination with a shaft rotatable on an axis, of a plurality of planetary baskets rotatable about axes revolvable around the axis of said shaft, means carried by said rotatable shaft for rotatably engaging said baskets, said baskets being rotatable on their own axes under an eccentric loading thereof and movable progressively with respect to said means by their rotatable engagement therewith and means rotatable on and relatively to said shaft for movably supporting said planetary baskets.
13. In a centrifugal machine, the combination with a rotary shaft, of a rotary housing rotatable with said shaft, a plurality of planetary baskets revolvable about the axis of said rotary shaft and progressively with respect to the outer wall of said housing, a distributor bowl rotatable on and relatively to said shaft, said distributor bowl discharging into said planetary baskets respectively, a bottom bearing plate rotatable on and relatively to said shaft, and means rigidly connecting said bottom bearing plate and the distributor bowl.
14. In a centrifugal machine, the combination with a rotary shaft, of a rotary housing driven by said shaft, a plurality of planetary baskets revolvable about the axis of said rotary shaft and rotatable about axes which are progressively movable with respect to the outer wall of said housing, a distributor bowl journalled upon said shaft, said distributor bowl being provided with spouts depending within said planetary baskets respectively, a bottom plate journalled on said shaft, and a baffle for each of said planetary baskets, said baffle rigidly connecting said bottom plate to the distributor spout in said planetary basket.
15. In a centrifugal machine, the combination with a rotary shaft, of a rotary housing mounted on and rotatable with said shaft, a plurality of planetary baskets rotatably engaging said rotary housing and progressively movable with respect to the outer wall of said housing, a distributor bowl journalled upon and rotatable relatively to said shaft, said distributor bowl being provided with spouts depending within said planetary baskets respectively, antifriction rollers journalled on said spouts and bearing on said planetary baskets, a bottom bearing plate journalled on and rotatable relatively to said shaft, and a baffle for each of said planetary baskets, said baffle constituting a rigid connection between said bottom bearing plate and the distributor spout corresponding thereto.
16. In a centrifugal machine, the combination of a rotary shaft, a spider frame mounted on the lower end of said rotary shaft, a rotary housing carried by said spider frame, said rotary housing being provided with a track-rail, a plurality of planetary separator baskets provided with treads in rolling engagement with said track-rail, an inner supporting frame comprising a distributor bowl journalled on and rotatable relatively to said shaft and discharging into said baskets respectively, a bottom plate journalled on and rotatable relatively to said shaft, a baffle extending upwardly through each of said separator baskets and rigidly connected to said bottom plate, and means rigidly connecting said baffle to said distributor bowl.
17. In a centrifugal machine, the combination of a rotary shaft, a spider frame mounted on the lower end of said rotary shaft, a rotary housing carried by said spider frame, said rotary housing being provided with upper and lower track-rails, a plurality of planetary separator baskets provided with axially-spaced treads in rolling engagement with said upper and lower track-rails, a distributor bowl journalled on and rotatable relatively to said shaft and provided with charging spouts depending into said baskets respectively, a bottom plate journalled on and rotatable relatively to said shaft, and a baffle mounted on said bottom plate and extending upwardly through each of said separator baskets, said baffles being connected to said spouts respectively.
18. In a centrifugal machine, the combination of a rotary shaft, a spider frame mounted on the lower end of said rotary shaft, a rotary housing carried by said spider frame, said rotary housing being provided with upper and lower track-rails, a distributor bowl journalled on and rotatable relatively to said shaft and discharging into said baskets respectively, a bottom plate journalled on said shaft, a rigid connection between said distributor bowl and said bottom plate, and a plurality of planetary separator baskets provided with axially-spaced treads whereby they are rotatably supported between said track-rails and said rigid connections.
19. In a centrifugal machine, the combination of a rotary shaft, a cylindrical housing secured to and rotatable with said shaft, said rotary housing being provided with upper and lower circular tracks concentric with said shaft, a plurality of separator baskets, each of said separator baskets comprising axially-spaced annular plates provided with treads extending around the inner peripheries of

said annular plates, said treads being in rolling engagement with said upper and lower circular tracks, and cylindrical screens extending between and secured to the outer peripheries of said annular plates, a distributor bowl freely journalled on said shaft and provided with charging spouts depending into said baskets respectively, a bottom plate also freely journalled on said shaft and baffles extending upwardly through said separator baskets and rigidly connecting said spouts to said bottom plate, said distributor bowl, charging spouts, baffles, and bottom plate forming a unit which is adapted to be rotated relatively to the rotary shaft and housing by means of the rotation of said separator baskets when eccentrically loaded.
